POWER DRIVE UNIT FOR A SPIN CASTING FISHING REEL OR SIMILAR ARTICLE

Raymond T. Cassidy, Stratford, Conn., assignor to Sperry Rand Corporation, New York, N.Y., a corporation of Delaware

Filed Sept. 14, 1964, Ser. No. 81,722

Term of patent 14 years

(Cl. D26—5)

FIG. 1.

FIG. 2.

FIG. 1 is a front perspective view of a power drive unit for a spin casting fishing reel or similar article, embodying my new design; and

FIG. 2 is a rear perspective view thereof.

The essential features of the design reside in the portions shown in solid outline.

The broken line showing of the spin casting fishing reel has been omitted from FIG. 1 for convenience in illustration.

I claim:

The ornamental design for a power drive unit for a spin casting fishing reel or similar article, substantially as shown and described.
